RAILWAY SIGNALING

Filed Jan. 16, 1930

UNITED STATES PATENT OFFICE

THOMAS J. O'MEARA, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY SIGNALING

Application filed January 16, 1930. Serial No. 421,150.

My invention relates to railway signaling, and has for an object the provision of novel and improved means for controlling signals from a remote point, such as a despatcher's office. My invention is particularly well adapted for, although not limited to, apparatus for the control of what are known as "take siding" signals.

I will describe one form of apparatus embodying my invention, and will then point out the novel features thereof in claims.

The accompanying drawing is a diagrammatic view showing one form of railway signaling apparatus embodying my invention.

Referring to the drawing, the reference characters 1 and 1^a designate the track rails of a stretch of main track M, which track is provided with a switch G leading into a siding F. The track rails 1 and 1^a are divided by insulated joints 17 to form a track section X—Y which is located in the rear of the switch G, and this track section is provided with the usual track circuit comprising a battery 2 and a track relay E.

Located in the rear of the switch G, and within the limits of the track section X—Y, is a "take siding" signal S, which, as here shown, comprises an electric lamp. When this lamp is lighted, the signal indicates to a train moving toward the right that the train is to enter the siding F, and that the engineer should control the train accordingly.

Associated with the signal S are two selectors D^T and D^C. Each of the selectors comprises an operating winding 5, and a normally open contact 7 which becomes momentarily closed when the selector is operated by the code impulse combination to which it is designed to respond. Each selector also comprises an answer-back winding 6, which is in inductive relation to the associated operating winding 5, and the function of which will be explained hereinafter. The operating windings 5 of the two selectors D^T and D^C are connected with a transmission line J leading to a despatcher's office, which is provided with code keys K^T and K^C for causing operation of selectors D^T and D^C, respectively, in the

usual manner. Also connected across the line J in the despatcher's office, is a head phone P.

The circuits for the control of the signal S may best be explained in connection with the operation of the apparatus as a whole, and I will accordingly assume that the despatcher desires to energize signal S. To do this, he will operate code key K^T, thereby causing selector D^T to momentarily close its contact 7. A "take-siding" relay B will then become energized by virtue of a circuit which passes from a battery 4, through the winding of relay B, answer-back winding 6 on selector D^T, contact 7 of this selector, and a switch-operated contact 3 to battery 4. Contact 3 is normally closed, but opens when the switch G is reversed to admit a train to the siding F. While contact 7 of selector D^T is closed, and before the relay B responds, periodically interrupted current will be supplied to the answer-back winding 6 of selector D^T, by a circuit which passes from battery 4, through contact 16 and winding 15 of a buzzer H, back point of contact 9 of relay B, winding 6 of selector D^T, contact 7 of this selector, and switch contact 3 to battery 4. This periodically interrupted current in winding 6 will induce an alternating current in winding 5 of selector D^T, and this alternating current will in turn cause a buzz in the head phone P, which buzz will inform the despatcher that selector D^T has responded. As soon as the back point of contact 9 of relay B opens, the buzzer H will, of course, become deenergized, and so the cessation of the buzz will indicate to the despatcher that relay B has picked up. When relay B closes, a stick circuit for this relay will become closed, which circuit passes from battery 4, through the winding of relay B, front contact 8 of relay B, back contact 14 of a relay C, and switch contact 3 to battery 4. When the train enters section X—Y, it will open track relay E, whereupon a relay A will become energized by a circuit which includes a battery 18, back contact 11 of relay E, front contact 10 of relay B, and the winding of relay A. Relay A will then close, with the result that the lamp of signal S will become

lighted by virtue of a circuit which includes this lamp, battery 13, and front contact 12 of relay A. When switch G is reversed to admit the train in siding F, contact 3 will open, thereby opening the stick circuit for relay B with the result that this relay will become deenergized, and so the parts of the apparatus will be restored to the conditions in which they are shown in the drawing.

10 I will now assume that after having energized the take-siding signal S the despatcher desires to withdraw the take-siding indication. To do this, he will operate his code key K^c, thereby causing selector D^c to respond in such manner as to momentarily close its contact 7. While contact 7 of this selector is closed, relay C will be energized by a circuit which passes from battery 4, through the winding of relay C, winding 6 and contact 7 of selector D^c, and switch contact 3 to battery 4. The closing of relay C will open the stick circuit for relay B at back contact 14, so that relay B will become deenergized. During the brief interval of time between the closing of contact 7 of selector D^c and the release of relay B, current will flow from battery 4, through the buzzer H, front point of contact 9 of relay B, winding 6 and contact 7 of selector D^c, and contact 3 to battery 4. The periodically interrupted current which then flows in the answer-back winding 6 will induce an alternating current in winding 5 of selector D^c, and the latter current will cause a buzz in the telephone P.

15 20 25 30 35 40 45 50 55 60 65 The beginning of this buzz will indicate to the despatcher that the selector D^c has responded, and the cessation of the buzz will indicate that relay B has released. The buzz due to the operation of the cancelling selector D^c will last slightly longer than the buzz due to the take-siding selector D^t, because relay B will require a longer time to release than it does to pick up.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a railway track provided with a switch leading into a siding, said track being divided by insulated joints to form a track section in the rear of said switch, a track circuit including a track relay for said section, a "take-siding" signal located in the rear of said switch and within the limits of said track section, a relay A for the control of said signal, a "take-siding" relay B, a circuit for relay A controlled by a front contact of relay B and a back contact of said track relay, a "take-siding" selector and a "canceling" selector, each having a normally open

contact, means controlled from a distant point for operating either of said selectors to momentarily close the associated contact, a pick-up circuit for relay B including the contact of said "take-siding" selector and a normally closed contact which opens when said switch is opened, a normally open relay C, a circuit for relay C including the contact of said cancelling selector and said switch contact, a stick circuit for said relay B including a front contact thereof and a back contact of relay C as well as said switch contact, an answer-back winding on each of said selectors, a buzzer, a circuit for the answer-back winding on the "take-siding" selector including said buzzer and a back contact of said relay B.

2. In combination, a railway track provided with a switch leading into a siding, said track being divided by insulated joints to form a track section in the rear of said switch, a track circuit including a track relay for said section, a "take-siding" signal located in the rear of said switch and within the limits of said track section, a relay A for the control of said signal, a "take-siding" relay B, a circuit for relay A controlled by a front contact of relay B and a back contact of said track relay, a "take-siding" selector and a "canceling" selector, each having a normally open contact, means controlled from a distant point for operating either of said selectors to momentarily close the associated contact, a pick-up circuit for relay B including the contact of said "take-siding" selector and a normally closed contact which opens when said switch is opened, a normally open relay C, a circuit for relay C including the contact of said cancelling selector and said switch contact, and a stick circuit for said relay B including a front contact thereof and a back contact of relay C as well as said switch contact.

3. In combination, a railway track provided with a switch leading into a siding, a "take-siding" signal located in the rear of said switch, a relay B for the control of said signal, a "take-siding" selector and a "canceling" selector, each having a normally open contact, means controlled from a distant point for operating either of said selectors to momentarily close the associated contact, a pick-up circuit for relay B including the contact of said "take-siding" selector and a normally closed contact which opens when said switch is opened, a normally open relay C, a circuit for relay C including the contact of said cancelling selector and said switch contact, a stick circuit for said relay B including a front contact thereof and a back contact of relay C as well as said switch contact, an answer-back winding on each of said selectors, a buzzer, a circuit for the answer-back winding on the "take-siding" selector including

said buzzer and a back contact of said relay B, and a circuit for the answer-back winding on said cancelling selector including said buzzer and a front contact of said relay B.

- 5 4. In combination, a railway track provided with a switch leading into a siding, a "take-siding" signal located in the rear of said switch, a relay B for the control of said signal, a "take-siding" selector D^a and a "cancelling" selector D^c, each having a normally open contact, means controlled from a distant point for operating either of said selectors to momentarily close the associated contact, a pick-up circuit for relay B including the contact of said "take-siding" selector and a normally closed contact which opens when said switch is opened, a normally open relay C, a circuit for relay C including the contact of said cancelling selector and said switch contact, and a stick circuit for said relay B including a front contact thereof and a back contact of relay C as well as said switch contact.
